Multifunctional Pen, #3018A, as shown on www.jaguarpen.com, dated Feb. 6, 2007 (1 page).*

Primary Examiner—Elizabeth A. Albert*Assistant Examiner*—Karen E Eldridge Powers(74) Attorney, Agent, or Firm—Christensen O'Connor Johnson Kindness PLLC(57) CLAIM

The ornamental design for a pen, as shown and described.

DESCRIPTION

FIG. 1 is an upper front right perspective view of a pen showing my new design;

FIG. 2 is a left side elevation view of the pen shown in FIG. 1;

FIG. 3 is a top plan view thereof;

FIG. 4 is a front elevation view thereof;

FIG. 5 is a right side elevation view thereof;

FIG. 6 is a bottom plan view thereof; and,

FIG. 7 is a rear elevation view thereof.

The stippling in the drawings represents a texture on the surface of the pen.
